www.NielsenPatents.com(57) **CLAIM**

The ornamental design for a shade tent, as shown and described.

DESCRIPTION

FIG. 1 is a top and side perspective view of a shade tent showing a new design;

FIG. 2 is a front view thereof;

FIG. 3 is a back view thereof;

FIG. 4 is a right side view thereof;

FIG. 5 is a left side view thereof; and,

FIG. 6 is a top view thereof.

The bottom view forms no part of the claimed design.

All of the dashed lines in the window are of FIG. 1 represent environmental conditions only and form no part of the claimed design. All other dashed lines of FIG. 1 represent seam lines. All of the dashed lines of FIGS. 2 and 3 represent seams.

All of the dashed lines in the window area of FIGS. 4 and 5 represent environmental conditions only and form no part of the claimed design. All of the dashed lines of FIG. 6 represent environmental conditions only and form no part of the claimed design.
